METHOD OF AND APPARATUS FOR
MAKING WINDOW BAGS

Harold Smithwick, Scarsdale, N. Y., and Peter Halbo, Cranford, N. J., assignors, by mesne assignments, to Ramco, Inc., a corporation of Delaware

Application May 4, 1933, Serial No. 669,344

15 Claims.

(Cl. 93—19)

This invention relates to methods and apparatus for making window bags. By window bag is meant a bag composed in part of transparent material and in part of relatively opaque material. That portion of the bag which is composed of transparent material affords a view of the contents of the bag. The relatively opaque material is generally less expensive than the transparent material and is therefore used for purposes of economy. Moreover, it is relatively difficult to print certain transparent materials such as cellulose acetate, regenerated cellulose, etc. and the relatively opaque material affords a more suitable surface for imprinting whatever legend or design it may be desired to place upon the bag.

In United States Patent 1,887,680, granted November 15, 1932 to Harold E. Hallman, there is disclosed a form of bag-making machine adapted to manufacture window bags from continuous webs of transparent and relatively opaque materials in such manner that the transparent panel extends lengthwise of the finished bag and preferably for the full length of the same.

In the apparatus disclosed in the aforesaid Hallman patent, bags may be manufactured from a wide web of relatively opaque material and a narrower web of transparent material, the opaque material being first folded into a partial tube and the transparent material being then fed in position to overlie the inturned margins of the first web and to bridge the gap between them.

The webs are then united by means of adhesive to form a complete tube and the tube thus made is successively severed into bag blanks, the manufacture of the blanks into bags being completed in the usual way.

Our invention relates particularly to the manner in which the individual bag blanks are formed or severed from the tube and has for an object an improvement in the method and apparatus for severing the materials, and more particularly the web of transparent material.

Our invention has for further objects such additional advantages and improvements as may hereinafter be found to contain.

Our invention contemplates continuously folding a web of relatively opaque material, such as glassine, into a partial tube, and feeding a narrower web of transparent material, such as "cellophane", into position to overlie the inturned margins of the first web and to bridge the gap between them, adhesive being applied to cause adherence of the webs to each other and thus to complete the formation of the bag tube,

While our invention contemplates progressing the bag tube thus formed past a severing device of the usual serrated character for the purpose of cutting the continuous bag tube into individual bag blanks, our invention contemplates making transverse cuts or slits across that portion of the transparent web destined to lie between the edges of the inturned margins of the relatively opaque web, at intervals corresponding to the length of the individual bag blanks and coinciding with the 10 serrated cuts made by the severing device.

This pre-cutting or pre-slitting of the transparent web thus provides straight and smooth edges at the ends of the individual bag blanks over that portion of the transparent web lying 15 between the edges of the inturned margins of the relatively opaque material.

As is well known, the conventional form of severing device leaves the severed material with a serrated edge. While serrated edges of this character are not objectionable so far as the relatively transparent materials are concerned, we have found that regenerated cellulose and other transparent materials are not well adapted to be cut with serrated edges and we have also found that conventional severing devices which leave the materials cut with serrated edges as described do not operate as satisfactorily as would be desired upon "cellophane" and other transparent materials which are amorphous rather than 30 fibrous in character.

Preferably, this is accomplished according to our invention by die-cutting transverse slits in the web of "cellophane" or other transparent material as it approaches the point at which it is combined with the folded web of relatively opaque material. Preferably, the slitting of the transparent web is accomplished as the latter passes over a hard metal roll by means of a revolving straight-edged knife which at periodic 40 intervals bears sharply against the web of transparent material passing over the hardened roll and cuts or slits the material.

The die-cutting or slitting is preferably accomplished at a point where the transparent material is under no tension, as the low tensile strength of this material combined with the fact that the slits ordinarily extend across the greater portion of the transverse dimension of the material would result in tearing or rupture of the web of transparent material if the latter were subjected to a tensile force after being slit. We accomplish this by providing two additional auxiliary rolls driven at peripheral speeds identical with that of 50 55

the hardened roll against which the cutting die is caused to bear.

The web of transparent material passes first between one of these auxiliary rolls and the draw roll or cutting roll, and then around a portion of the surface of the draw roll and finally between the second auxiliary roll and the draw roll where it is met by and joins the web of relatively opaque material. The die cutting is done as the web of transparent material travels over the surface of the draw roll between the points of engagement with the first and second auxiliary rolls, respectively, and, due to the uniform peripheral speeds of the three rolls, the web of transparent material is advanced through the cutting or slitting point under substantially no tensile force. Nor is the web of transparent material subjected to any tensile force after being slit and prior to being combined with and attached to the web of relatively opaque material.

Our invention also contemplates the provision of means whereby the distance between successive die-cuts or slits in the web of transparent material may be varied in accordance with the predetermined length of the individual bag blanks with a minimum of difficulty.

In order that our invention may be clearly set forth and understood, we now describe, with reference to the drawings accompanying and forming a part of this specification, a preferred form and manner in which our invention may be practiced and embodied. In these drawings,

Fig. 1 is a more or less diagrammatic side-elevational view of a bag-making machine constructed in accordance with our present invention;

Fig. 2 is a vertical sectional view, on an enlarged scale, of a portion of the apparatus shown in Fig. 1, taken on the line 2—2 of Fig. 1;

Fig. 3 is a plan view of the apparatus shown in Figs. 1 and 2;

Fig. 4 is a side-elevational view of apparatus shown in Figs. 2 and 3, taken on the line 4—4 of Fig. 3;

Fig. 5 and 6 are vertical sectional views of apparatus shown in Figs. 2, 3 and 4, taken on the lines 5—5 and 6—6, respectively, of Fig. 3;

Fig. 7 is a plan view of a portion of the apparatus shown in Fig. 1;

Fig. 8 is a plan view of a portion of a window blank made on the machine shown in the preceding figures; and

Fig. 9 is a transverse sectional view of the blank shown in Fig. 7, taken on the line 9—9 of Fig. 8.

Similar reference numerals designate similar parts in the several views of the drawings.

Referring now to the drawings, and more particularly to Fig. 1 thereof, the bag tube is made from a continuous web 1 of relatively opaque material, such as glassine, and a continuous web 2 of transparent material, such as regenerated cellulose, supplied from rolls 3 and 4, respectively, of the materials.

The web 1 is fed from a roll 3 over guide rolls 5 and 6 and over a forming plate 8 which determines the width of the front of the bag. The side portions of the web 1 are turned downward outside the lateral edges of the plate 8 by means of deflectors 9 located on either side of the plate 8, while gussets are formed in the sides of the bag by means of gusseting plates 11 and a second forming plate 12, while the marginal portions of the web 1 are folded in under the plate 12 by means of folders 13, in the manner set forth and

described in the aforesaid Letters Patent No. 1,887,680 to Hallman. As in the aforesaid patent, the free margins of the glassine web 1 are not folded into overlapping relation, but a substantial gap is left between them, as indicated in Figs. 5 and 9.

The relatively narrow web 2 of transparent material is drawn from the roll 4 over rollers 15, 16 and 17, glue or other adhesive being applied to the margins of the web as the web 2 passes over the roller 15 by means of gumming rollers 18 partly immersed in a glue pot 19. The web 2 then passes between a roller 20 and a hardened steel draw roll 21 contiguous thereto, around the roll 21 and between the latter and three relatively narrow draw rollers 22, where it is joined by the web 1. The two outer draw rollers 22 are adjusted to act through marginal notches 8a in the forming plate 8 to engage the overlapping margins of the webs 1 and 2, while the middle roller 22 cooperates with the wide roll 21 through an opening 8b in the forming plate 8 to grip the webs 1 and 2 at a median point. The pressure of the roll 21 and the rollers 22 causes the gummed margins of the web 2 to adhere to the infolded margins of the web 1, thus completing the gusseted bag tube, which advances along the forming plate 8, where it is severed by means of a stationary blade 30 located above the end of the plate 8 and a bar 31 adapted to rotate in a plane normal to that of the bag tube, thus making a succession of upward transverse severing strokes. The intervals between successive strokes of the bar 31 are regulated with respect to the speed of advancement of the bag tube formed from the combined webs 1 and 2 to sever the tube into bag blanks of predetermined length.

The blade 30, as shown in Fig. 7, is provided with a concave saw-toothed edge 33 adapted to cut the gussets and upper face of the bag tube when the moving bar 31 makes its upward stroke, while the end of the forming plate 8 is provided with saw-toothed edges 34 adjacent to and immediately below the outer ends of the serrated portion 33 of the blade 30, and an intermediate edge 35, which may be free from serrations as shown. The width of the edge portion 35 is made substantially equal to the distance between the infolded marginal edges of the web 1. The serrated edges 34 of the forming plate 8 cooperate with the bar 31 to sever the remaining portions of the web 1, as well as the marginal portions of the web 2 located outside of the infolded marginal edges of the web 3.

At the time of severing, the work is gripped between a roller 40 and a gripping bar 41 carried by a cooperating roller 42, the arrival of the gripping bar 41 in gripping position being timed to coincide with the severing of the material by the upward thrust of the bar 31.

As in the aforesaid Hallman patent, the bag blank next passes between a feed roll 43 and a co-operating feed segment 44 and thence to a folding and pasting coupler comprising cylinders 45 and 46, the cylinder 46 carrying a tucking blade 47 and a pasting bar 48, while the cylinder 45 carries a folding and gripping jaw 51 and a pasting bit 52. The rotation of the cylinders 45 and 46 is timed with relation to the arrival of the bag blanks to tuck and fold over the leading end of each bag blank and paste it against the back of the bag body. The finished bags pass from the cylinders 45 and 46 to a delivery and drying conveyor 53.

Prior to the severing of the tube by means of the

bar 31, the end of the forming plate 8 and the stationary blade 30, the web 2 of transparent material is transversely slit at intervals corresponding to the lengths of the severed bag blanks, the lengths of the slits being substantially equal to the distance between the infolded marginal edges of the web 1. The slitting of the web 1 is accomplished as the latter passes over the hardened surface of the draw roll 21 by means of a rotating die or knife blade 60 which bears sharply against the web 2 on the surface of the roll 21 at intervals corresponding to the intervals between successive severing actions of the bar 31.

According to our invention, we provide means for readily adjusting the intervals between successive slittings of the web 2 by means of the knife blade 60, as well as means for adjusting the positions of the slits to correspond with the subsequent severing of the web 2 into blanks in the manner described hereinabove. Such means, together with the details of the mounting of the various parts and the manner in which the parts are driven, will now be described.

The hardened steel draw roll 21 is mounted upon a shaft 61, journaled in brackets 62 and 63, respectively, which are mounted upon the main frame members 64 which support the machine. The shaft 61 carries at one end a gear 66 adapted to mesh with a driving gear 67 driven by suitable means (not shown). The opposite end of the shaft 61 carries a pair of relatively adjustable gears 70 and 71. The gear 70 is keyed to the shaft 61 while the gear 71 is not, but the gears 70 and 71 are rigidly fastened together by means of suitable fasteners 72 attached to the gear 71 and extending through slots 73 in the gear 70. By means of the fasteners 72 and the slots 73 the relative positions of the gears 70 and 71 may be varied at the will of the operator.

The rollers 22 are mounted upon a shaft 75 journaled in bearing members 76 forming extensions of the brackets 62 and 63 and carrying a gear 77 adapted to mesh with the gear 70, by means of which the shaft 61 is caused to drive the shaft 75. The diameters of the draw rollers 22 are made equal to the diameter of the draw roll 21, and the gears 70 and 77 being of equal size, the rolls 22 and 21 are caused to operate at identical peripheral speeds.

The knife blade 60 is mounted in a holder 80, carried by a shaft 81, journaled in lugs 83 forming part of bracket members 84, mounted upon a shaft 85 held in bearing blocks 86, mounted upon the frame members 64. The brackets 84 are provided with recessed portions 87 in which are mounted metal bearing plates 88 having rubber backing blocks 89 and secured to the brackets 84 by means of fasteners 90. The positions of the brackets 84 are determined by means of set-screws 92, having lock nuts 93, and passing through bars 94 terminating in flanges 95. The flanges 95 are adjustably mounted upon the frame members 64 by means of suitable fasteners 96 passing through curved slots 97 in the flanges 95.

By means of the set-screws 92, which bear against the surfaces of the plate 88, the brackets 84 are mounted in such position as to bring the outer edges of the knife 60 into sharp engagement with the surface of the draw roll 21 at such time as the edge of the knife 60 passes through a plane passing through the centers of the shafts 61 and 81, the knife 60 at this time bearing against the transparent web 2 passing over the surface of the draw roll 21 and slitting the same transversely.

In this position, a gear 99 keyed to the shaft 81

meshes with the gear 70, thus providing means for driving the shaft 81 to rotate the knife blade 60. In Figs. 2, 3 and 4, a knife blade 60 and a gear 99 are provided which are of such size as to provide transverse slits in the web 2 at relatively frequent intervals, and the brackets 84 are set accordingly by means of the flanges 95 and the set-screws 92. In Figs. 5 and 6, however, the knife blade 60, the holder 80 and the gear 99 are of such size as to slit the web 2 at relatively widely spaced intervals corresponding to relatively long bag blanks, and the brackets 84 are set accordingly.

In order to manufacture bag blanks of different lengths I provide a suitable number of blade holders 80, blades 60, and gears 99, which may readily be substituted for each other in order to vary the spacing of the slits in the cellophane web 2.

The draw roller 20 is also driven from the shaft 61. This roller 20 is mounted upon a shaft 100 journaled in a pair of arms 101, and carries a gear 102 adapted to mesh with the gear 70. The arms 101 are fastened to a pair of L-shaped bars 103 mounted upon the blocks 62 and 63.

By means of an idler gear 105 mounted upon a short shaft 106 journaled in the block 62 and meshing with the adjustable gear 71, the shaft 61 drives a gear 107 which is keyed to a shaft 108 carrying a roller 109 adapted to cooperate with a roller 110 to grip the web 1 of relatively opaque material and advance it into the grip of the rollers 21 and 22. It will therefore be apparent that by varying the angular relation of the gears 70 and 71, the relative positions of the webs 1 and 2 may be varied with respect to each other in such manner as to cause the slits made in the web 2 by the knife 60 to coincide with severings of the bag blank by means of the moving bar 31.

It will further be apparent that, due to the fact that the web 2 of transparent material is slit as it passes over the surface of the hardened roll 21 between points of engagement with the rollers 20 and 21, and 22 and 21, respectively, the transverse slit is not subjected to a tensional force which would tend to tear or disrupt the web 2. Moreover, at no time after the web 2 is slit by means of the knife 60 is it subjected to a tensional force which would tend to tear or otherwise injure the web 2 at the point where it is slit.

The appearance of the severed end of the bag blank is illustrated in Fig. 8, from which figure it will be seen that the ends of the web 2 lying between the infolded marginal edges 120 of the web 2 are not saw-toothed as are the remaining portions of the ends of the bag blank, but are smooth and straight. Window bags thus made in accordance with our present invention are much less subject to injury to the window portions thereof than windows bags in which the entire bag 2 is severed in such manner as to leave the ends of both the transparent and opaque material with saw-toothed edges.

It will be obvious to those skilled in the art that while we have described our invention hereinabove with respect to a preferred form and embodiment, our invention is not limited to the details of this illustrative example, but may variously be embodied within the scope of the claims hereinafter made.

We claim as our invention:

1. In a machine for making window bags, in combination, means for forming a partial tube from a relatively wide web of material, means for applying a relatively narrow web of material to complete said tube, means to slit smoothly said relatively narrow web transversely thereof at 75

- predetermined intervals prior to the point at which said webs are combined, and means to sever serrately the remainder of the tube transversely and coincidently with the said slits.
5. 2. In a machine for making window bags, in combination, means for forming a partial tube from a relatively wide web of material, means for applying a relatively narrow web of material to complete said tube, and a rotating knife device adapted to slit said narrow web transversely at regularly spaced intervals prior to the point at which said relatively narrow web is applied to said relatively wide web.
10. 3. In a machine for making window bags, in combination, means for forming a partial tube from a relatively wide web of material, means for applying a relatively narrow web of material to complete said tube, a knife adapted to make transverse smooth-edged slits of a length less than the width of said relatively narrow web in said web prior to the point at which said web is applied to the partial tube formed from said relatively wide web, and means to transversely sever the formed tubes along serra lines at points coinciding with said transverse slits.
15. 4. In a machine for making window bags, in combination, means for forming a partial tube from a relatively wide web of material, means for applying a relatively narrow web of material to complete said tube, means for serrately severing the tube thereby formed into notched-edge bag blanks, and means for slitting said relatively narrow web transversely over a portion of its width prior to the point at which it is applied to said relatively wide web at intervals corresponding to the intervals between successive severings of said tube into bag blanks whereby the notched edge does not extend across said narrow web.
20. 5. In a machine for making window bags, in combination, means for forming a partial tube from a relatively wide web of material, means for applying a relatively narrow web of material to complete said tube, and a rotary knife having a peripheral speed equal to that of said webs and adapted to make transverse cuts in said relatively narrow web at predetermined intervals prior to the point at which said webs are combined.
25. 6. In a machine for making window bags, in combination, means for forming a partial tube from a relatively wide web of material, means for applying a relatively narrow web of material to complete said tube, knife means adapted to slit said relatively narrow web transversely prior to the point at which said webs are combined, and means for varying the intervals between successive slits made by said knife means.
30. 7. In a machine for making window bags, in combination, means for forming a partial tube from a relatively wide web of material, means for applying a relatively narrow web of material to complete said tube, a rotary knife adapted to slit said relatively narrow web transversely at intervals prior to the point at which said webs are combined, and means for varying the spacing of said slits independently of the speed of said webs.
35. 8. In a machine for making window bags, in combination, means for forming a partial tube from a relatively wide web of material, means for applying a relatively narrow web of material to complete said tube, a rotary knife adapted to slit said relatively narrow web transversely at intervals prior to the point at which said webs are combined, and means for varying the spacing of said slits.
40. 9. In a machine for making window bags, in combination, means for forming a partial tube from a relatively wide web of material, means for applying a relatively narrow web of material to complete said tube, including a roll having a hard surface adapted to be traversed by said relatively narrow web, and a rotary knife adapted to bear against said relatively narrow web at intervals as it traverses said roll to slit said narrow web transversely over a portion of its width.
45. 10. In a machine for making window bags, in combination, means for forming a partial tube from a relatively wide web of material, means for applying a relatively narrow web of material to complete said tube, including a roll having a hard surface adapted to be traversed by said relatively narrow web, a second roller adapted to cooperate with said first-mentioned roll to grip and advance said narrow web, a third roller adapted to cooperate with said first-mentioned roller to grip and advance said narrow web at a subsequent point, and a rotating knife device adapted to bear against said narrow web at intervals as it passes over said first-mentioned roll between said second roll and said third roller to slit said narrow web transversely.
50. 11. In the method of making window bags by combining a relatively wide web and a relatively narrow web to form a tube and serrately severing said tube at intervals, the step which comprises smoothly slitting said relatively narrow web transversely over a portion of its width at intervals corresponding to the length of the blanks formed by severing said tube whereby the serrations do not extend across said narrow web.
55. 12. The method of making window bags which comprises forming a relatively wide web of material into a partial tube, applying to said web to complete the tube a relatively narrow web of transparent material, forming transverse smooth-edged slits in said relatively narrow web before joining said webs, and serrately severing the remainder of tube at intervals coinciding with the slits in said relatively narrow web.
60. 13. Apparatus for making window bags from a relatively wide web of material and a relatively narrow web of transparent material which comprises means for forming said wide web into a partial tube, means for applying said narrow web thereto, means adapted to slit said narrow web transversely along smooth-edged lines at intervals, and means for severing the tube thereby formed at intervals substantially coinciding with the slits in said narrow web, said means for severing the tube comprising a serrated knife.
65. 14. Apparatus for making window bags from a relatively wide web of material and a relatively narrow web of transparent material which comprises means for infolding the edges of said wide web to form a partial tube, means for smoothly slitting said narrow web at intervals transversely over a width substantially equal to the distance between the infolded marginal edges of said wide web, means for applying said slit narrow web to said wide web to form a complete tube, and means for serrately severing said tube at intervals coinciding with the spacing of the slits in said narrow web.
70. 15. A machine for making window bag blanks from two webs of different widths, which comprises a forming plate, folders for folding marginal edges of the relatively wide web about the

forming plate, means for superimposing the margins of said narrow web on the infolded margins of said wide web to form a tube comprising a pair of cooperating rollers, said forming plate continuing beyond said rollers and terminating in a severing edge, a moving member adapted to cooperate with said severing edge to sever the tube into a plurality of bag blanks, and a knife device

adapted to cooperate with one of said rollers to slit the narrow web transversely prior to the point where the two webs are combined at spaced points coinciding with the ends of the blanks formed by said severing member.
